UNITED STATES PATENT OFFICE

DAVID SPAHN, OF WHEATLAND, WYOMING.

HARROW.

Application filed September 17, 1925. Serial No. 56,963.

This invention relates to an improved harrow structure together with novel draft means for connecting the same to a cultivator or similar machine.

5 One object is to generally improve upon the adjustable harrow structure disclosed in a prior patent bearing No. 1,539,441, granted to me on May 26th, 1925.

As in the patent referred to, it is one of 10 the outstanding objects in this case to provide an improved means for adjusting the sections of the harrow frame both in width and length, while at the same time adding greater strength to the structure.

15 An equally important feature of the present invention is the novel attaching means provided for connecting the harrow to a cultivator, this means embodying an advantageous coupling for securing the structure 20 in a manner to obtain the most advantageous line of draft.

Other features and advantages of the invention will become apparent from the following description and drawings.

25 In the accompanying drawings forming a part of this application and in which like numerals are employed to designate like parts throughout the same:—

Figure 1 is a side view of a harrow constructed in accordance with the present invention showing the novel suspension and attachment means therefor.

Fig. 2 is a top plan view of the suspension and attaching means.

35 Fig. 3 is a top plan view of the harrow structure with the means in Fig. 2 removed.

Fig. 4 is a central cross section through the structure shown in Fig. 3.

Fig. 5 is a detail view of one corner of the 40 harrow structure.

Fig. 6 is a perspective view of one of the frame bars of the harrow.

Referring to the drawings in detail, the reference character 1 designates generally 45 the frame of the harrow. This is made up of a plurality of substantially duplicate flat bars 2, each of which is provided with openings for passage of the threaded upper end of the teeth 3. These teeth are clamped to the bars by the nuts as shown more plainly in Fig. 4.

It is only necessary to state in connection 55 with the teeth that it is preferable to have less teeth at the front of the structure than at the rear. This is plain by considering Fig. 3. Each bar has one end flat and dis-

posed in overlapping connected relation with a correspondingly shaped end of an adjacent bar. Moreover each bar has the opposite end bowed or bent longitudinally as 60 at 4. The relative arrangement of these bent ends 4 is obvious from a consideration of Fig. 5.

Two special connectors are associated with the harrow frame for expanding and contracting the same and securing the desired 65 rigidity of structure. One connector is indicated by the reference character 5 and the other one by the reference character 6.

The connector 5 is made up of a pair of 70 duplicate strips of metal represented by the characters 7. These strips are flat in form, being somewhat similar to the bars 2 used in the make-up of the aforesaid frame. The outer ends of the strips are flat and are connected with opposed corners of the frame. The inner adjacent ends however, are twisted as at 8 and the extremities 9 are thus disposed vertically and adjustably connected together as at 10. 75

At this time, I would direct attention to Fig. 4, wherein it will be seen that the overlapped adjustably connected ends 9 are provided with additional holes through which the connecting bolt may be selectively 80 passed. This permits the length of the connector to be varied for adjusting the harrow frame in width.

The connector 6 is in the form of a single 85 metal rod. The rod is of cylindrical cross 90 section and is provided at its front with a relatively large eye 11 and is provided at its opposite end with a plurality of bolt holes 12 through which the special eye bolt 13 is 95 adapted to be passed. In connection with this rod 15, I would call attention to the intermediate portion 14 which is bowed or arched to overlie the intermediate portion of the connectors 5 in spaced relation. In connection with this rod 6 I would call attention to the especially bent ends 4 of the aforesaid frame bars. These bent ends are connected with the rod as shown plainly in Fig. 5. From this figure, it is apparent that one end of one frame bar is bent downwardly and the other one upwardly and they thus substantially encircle the rod. 100

From the foregoing it will be seen that the harrow proper comprises a frame composed of a plurality of sections pivotally 110 connected at their ends in a manner to permit the frame to be adjusted in width and

length. This adjustment is made by means of the adjustably connected intersecting connectors, one of which comprises a cylindrical rod and the other of which comprises adjustably connected flat sections.

The suspension and hitching or attaching device comprises a cylindrical rod 15 embodying a down bent portion 16 and a horizontally bent portion 17. At the major part of this member 15 are clevises 18 with which hangers 19 are connected, these hangers being provided at their opposite ends with attaching eyes. The eye on the lower end of the foremost member 19 is connected with the relatively large eye 11 of the forward end of the connector rod 6. There is an additional connection 20 between this eye 11 and the horizontal portion 17. Moreover the extremity of this portion 17 is directed at right angles as at 21 and is connected with the correspondingly directed portion 22 of an L-shaped member 23. The short arm 24 of this member is provided with a seat for reception for a portion of a blade carrying shank 25 of the cultivator shovels or blade 26. In addition there is a clamping member 27 on the opposite side, this being connected with the part 24 by the bolts 28.

In connection with the angularly directed portions 21 and 22, I would state that these are constructed to permit the suspension means and harrow to be adjusted over toward one side of the shank 25. Moreover, the L-shaped member 23 of the hitching clamp can be reversed, that is, placed on the side of the shank where the part 27 is now shown.

It is believed that by carefully considering the description in connection with the drawings, persons familiar with structures of this class will be able to obtain a clear understanding of the invention, therefore a more lengthy description is thought unnecessary.

While the preferred embodiment of the invention has been shown and described, it is to be understood that minor changes coming within the field of the invention claimed, may be resorted to if desired.

Having thus described my invention, what I claim as new is:

1. In a structure of the class described, a harrow embodying a plurality of teeth and a carrying frame therefor, said frame being made up of adjustably connected sections, each section being flat at one end and having its opposite end curved longitudinally, the curved ends of the sections cooperating with each other and the flat ends cooperating with each other, and a cylindrical connecting rod connected with the curved end of said sections, said rod being provided at its front end with an attaching eye and being provided with a multiplicity of holes at its opposite end for adjustable connection with the adjacent part of the frame.

2. In a structure of the class described, a harrow embodying a toothed frame, of substantially rectangular form, said frame being made up of a plurality of adjustably connected sections, a pair of intersecting connectors connected with the corner portions of the frame, one connector embodying a pair of flat strips having their inner ends twisted to dispose them in vertical position, said vertically disposed portions being formed with apertures, a connecting bolt passing through the apertures, the other connector being in the form of a longitudinal cylindrical rod having an attaching eye at its front and having its opposite end provided with a plurality of bolt holes, the rod being bowed at its center to arch over the central portion of the first named connector.

3. In a structure of the class described, a suspension member, a harrow beneath said member, hangers between said member and harrow, and a hitching clamp for said member, said clamp embodying a substantially L-shaped member and attaching portions, the aforesaid member being provided at its forward end with a laterally directed portion adjustably connected with a portion of said L-shaped member.

In testimony whereof I affix my signature.

DAVID SPAHN.
